GARMENT

Thomas La Maida, University Heights, Ohio

Application February 3, 1938, Serial No. 188,503

3 Claims. (Cl. 2—224)

This invention relates to improvements in garments, and more particularly to means for preventing a form fitting garment from creeping, crawling, or wrinkling.

Objects of this invention are to provide a personal wear garment, which is cut to conform to the contours of the body and eliminates the possibility of creeping, and the gathering of excess quantities of material at certain parts of the body.

Another object is to provide a garment adapted to fit around the lower part of the trunk of a body, the same being constructed and designed in such a manner that it will not creep, wrinkle, or permit an excess of material to gather at the lower portion of the buttocks in the region of the bifurcation.

Another object is to provide a garment of the type described which can be worn either as an under garment or as an outer garment, and will keep its position, shape or fit regardless of strenuous body movements.

Another object is to provide a scientifically designed garment, affording perfect comfort and support to the wearer in all body positions.

Another object is to provide a garment construction which, regardless of its length or body movements, always remains sealed near the point of body bifurcation.

Other and further objects of the invention will become apparent during the course of the following description.

In the drawing forming a part of this specification:

Fig. 1 is a plan view of the patterns before they are sewed together,

Fig. 2 is a plan view of the patterns placed in position of assembly, with the reinforcement panel stitches in position,

Fig. 3 is a part sectional, part elevational view, looking into the seat of the garment,

Fig. 4 is a part sectional, part elevational view, looking into the front of the garment,

Fig. 5 is a perspective of the garment on a wearer, while

Fig. 6 is a front elevational of the garment on a wearer.

The invention herein described may be applied to various types of form fitting garments, either outer or under garments for men, women or children and may be manufactured of any suitable materials.

In the drawing, the blanks from which the garment is made, are illustrated in Figs. 1 and 2, wherein the numeral 10 illustrates a central

panel, while right and left front side gores are illustrated respectively by numerals 11 and 12, and right and left rear gores are indicated respectively by numerals 13 and 14. When certain types of materials are used a reinforcing member 15 may be provided. The upper end of the central panel 10 constitutes a front panel 16, having its longitudinal marginal edges cut in a concave configuration, as illustrated at 19 and 20, while the lower end of the panel 10 constitutes a rear panel 17, having its longitudinal marginal edges cut in a convex configuration, illustrated at 22 and 23. Centrally the panel 10 constitutes a crotch portion 18, recessed at 21 and 21a.

Right and left rear gores 13 and 14 are cut in convex configurations, as illustrated respectively at 24 and 25, while their upper marginal edges are cut in concave configurations, as illustrated at 26 and 27 respectively. Likewise right and left front gores 11 and 12 have marginal edges cut in concave configurations illustrated at 28 and 29, and their inner marginal edges illustrated at 30 and 31 respectively, similarly contoured. Convex margin 32 of right front side gore 11 and 25 convex margin 33 of rear gore 13 are adapted to be united as hereinafter described, likewise convex margin 34 of left front side gore 12 is adapted to be united to margin 35 of rear gore 14.

The manner of assembling and forming the garment is illustrated in Fig. 2 wherein marginal edges 30 and 31 of side gores 11 and 12 are united to marginal edges 19 and 20 of front panel 16 of central panel 10, by suitable means, as by overlapping one margin over the other and stitching therethrough, in a well known manner. Likewise marginal edges 24 and 25 of rear gores 13 and 14 are united to marginal edges 22 and 23 of rear panel 17, and marginal edges 32 and 33 of front gore 11 and rear gore 13 are united, and marginal edges 34 and 35 of front gore 12 and rear gore 14 are united.

If desired for certain uses, the reinforcing member or panel 15, having marginal recesses 36 and 37 corresponding to the marginal contours 21 and 21a of the central panel 10, may be placed over the lower portions of front panel 16 and side gores 11 and 12 and over the upper portions of rear panel 17 and rear gores 13 and 14 and sewn thereto, as shown in Fig. 2. The use of the reinforcing panel 15 is optional and may be conveniently used when the garment is made of light materials, of the type likely to creep or wrinkle in response to body movements. A garment incorporating my invention when designed

for female use may include straps 41 and 42, suitably secured to the front panel 16 and rear panel 17 respectively as by stitching, the straps being adapted to hold certain sanitary appliances.

5 The garment herein illustrated because of its particular shape, configuration and design is adapted to closely fit and conform to the shape and contour of a human body in the vicinity of the crotch and gluteo-inguinal areas, and thus 10 provides a comfortable personal wear garment. The desirability of having such garments remain in shape in such types of garments as bathing suits, panties, girdles, corsets and the like in spite of strenuous physical body and limb movements, 15 is obvious. I have discovered that by reinforcing such garment by a series of stitches at the proper place, creeping, crawling or wrinkling of the edge portions of such garment in the regions below the buttocks are prevented.

20 Accordingly, as shown in Figs. 2, 3 and 5, at 38 and 39 two series of U-shaped rows of stitches of thread of any desired type, are disposed in such a manner that they extend rearwardly and upwardly from the central lower rear margin of the 25 garment and cover and reinforce the areas of the garment covering the cheek or high point of the buttocks or the areas immediately therebelow. When certain heavy weight materials are used such stitching may cover two separate areas 30 in groups with an unstitched area portion positioned in the crotch portion of the garment as illustrated, whereas, in some instances wherein lighter materials are used the stitched area may extend continuously from one buttock area to the 35 other through the crotch portion. If desired, the stitching may also extend along the front portion of the garment for certain uses, as shown at 40. The completed garment is indicated by the numeral 43.

40 The stitching thus disposed has been found to retain the garment in a comfortable unwrinkled position by seating or retaining the rear lower portion of the garment on the buttocks or gluteo-inguinal areas. This construction presents an 45 additional advantage of preventing the garment from pulling away from or creeping in the crotch area due to stress and pulling strains in a direction from the crotch towards the buttocks; this feature being important when it is used in 50 exposed garments, such as bathing trunks, dancing trunks and the like. The stitching herein disclosed adds very little cost to the manufacturing of the garment and provides the advantages 55 above enumerated in a comfortable, attractive form fitting garment.

The invention, herein disclosed, may be used in men's garments, by altering the front of the garment in an obvious manner or in the manner illustrated in my co-pending application Serial 60 No. 174,538, and such modifications are within the contemplated scope of my invention.

65 It will be apparent to those skilled in the art that the garment herein disclosed may be variously changed, used or modified, without departing from the spirit of the invention or sacrificing the advantages thereof, and that the embodiment of my invention herein shown is illustrative only, and that my invention is not limited thereto.

I claim:

70 1. A form fitting bifurcated garment, comprising central front and rear panels connected by a narrow crotch portion, the longitudinal margins of the front panel being concave in configuration, the longitudinal margins of the rear panel 75 being convex in configuration, front gores having

cooperating margins concave in configuration and secured to said front panel margins, rear gores having cooperating margins convex in configuration and secured to said rear panel margins, the lower marginal portions of the gores 5 operating with the narrow crotch portion of the panel forming leg encircling portions, the position and arrangement of the cooperating front panel and front gores providing for freedom of leg movement of the wearer by providing excess 10 material above the crotch and on each side thereof, the position and arrangement of the cooperating rear panel and rear gores providing a supporting pocket for the buttocks of the wearer and preventing creeping and crawling of the 15 garment in the crotch portion in response to body movements.

2. A form fitting bifurcated garment, comprising central front and rear panels connected by a narrow crotch portion, the longitudinal margins 20 of the front panel being concave in configuration, the longitudinal margins of the rear panel being convex in configuration, front gores having cooperating margins concave in configuration and secured to said front panel margins, 25 rear gores having cooperating margins convex in configuration and secured to said rear panel margins, the lower marginal portions of the gores operating with the narrow crotch portion of the panel forming leg encircling portions, the position 30 and arrangement of the cooperating front panel and front gores providing for freedom of leg movement of the wearer by providing excess material above the crotch and on each side thereof, and two series of U-shaped rows of reinforcing 35 stitches positioned and arranged in such manner as to reinforce the rear panel and gores of the garment in the buttock regions adjacent the crotch portions, the position and arrangement of the cooperating rear panel, rear gores and said 40 reinforcing stitches providing a supporting pocket for the buttocks of the wearer and preventing creeping and crawling of the garment in the crotch portion in response to body movements.

3. A form fitting bifurcated garment, comprising 45 central front and rear panels connected by a narrow crotch portion, the longitudinal margins of the front panel being concave in configuration, the longitudinal margins of the rear panel being convex in configuration, front gores having 50 cooperating margins concave in configuration and secured to said front panel margins, rear gores having cooperating margins convex in configuration and secured to said rear panel margins, the lower marginal portions of the gores 55 operating with the narrow crotch portion of the panel forming leg encircling portions, the position and arrangement of the cooperating front panel and front gores providing for freedom of leg movement of the wearer by providing excess 60 material above the crotch and on each side thereof, the position and arrangement of the cooperating rear panel and rear gores providing a supporting pocket for the buttocks of the wearer and preventing creeping and crawling of the garment 65 in the crotch portion in response to body movements, a suitably secured reinforcing member coextensive with the entire crotch and the lowermost portions of the front and rear panels 70 and gores, two groups of reinforcing stitches passing through the reinforcing member, the rear panel, and the rear gores in the buttocks regions thereof, and cooperating straps disposed transversely of the crotch portion of the garment on the front and rear panels respectively in such 75

manner that they are adapted to retain the ends of an elongated sanitary appliance disposed longitudinally of the crotch when the garment is lowered from the wearing position along the body of a wearer, the form fitting of the garment due to the position and arrangement of the panels and gores in the vicinity of the crotch serving to

securely retain said sanitary appliance in position along the crotch portion of the body when said garment is being worn and to prevent displacement and lateral movement of the sanitary appliance in response to active body and limb movements.

5
THOMAS LA MAIDA.
